UNITED STATES PATENT OFFICE.

JAMES W. BROKAW, OF TACOMA, WASHINGTON.

COVER-FASTENER FOR SHIPPING-CASES.

1,178,990.

Specification of Letters Patent. Patented Apr. 11, 1916.

Application filed April 13, 1915. Serial No. 21,154.

To all whom it may concern:

Be it known that I, JAMES W. BROKAW, a citizen of the United States, residing at Tacoma, in the county of Pierce and State of Washington, have invented new and useful Improvements in Cover-Fasteners for Shipping-Cases, of which the following is a specification.

This invention relates to cover fasteners for shipping cases and consists in certain improvements in the construction thereof as will be hereinafter fully described and pointed out in the claims.

More particularly the invention is designed to fasten the cover of a shipping case and to strengthen the case.

The invention is illustrated in the accompanying drawings as follows:—

Figure 1 shows a perspective view of the shipping case. Fig. 2 is a vertical section of a fragment of the case showing a part of the device.

1 marks the walls of the case. These are annular walls and flare outwardly toward their upper edge. The receptacle is provided with a hoop 2 near the top and a hoop 3 near the bottom. A cover 4 is arranged on top of the receptacle. It has substantially the same diameter as the receptacle.

20 Two wires 5 and 6 are utilized for fastening the cover in place on the receptacle and for securing the hoop in place thereon. Each of these wires has a hooked end 7 which is hooked under the hoop 2. The 25 central portions of the wires are brought together and twisted at 9 thus securing the wires together and also tightening them over

the cover. This arrangement of fastening not only securely fastens the cover in place on the receptacle but also secures the hoop 40 2. Should there be any loosening of the hoop this may be readily tightened by continuing the twist 9.

In order to facilitate the placing of the hooks 7 under the hoop 2, I prefer to point the hooks 7. Where this is done they can be readily passed under the hoop without any previous notching of the walls 1.

What I claim as new is:—

1. In a shipping case, the combination of 50 a receptacle having annular walls flaring outwardly toward their upper edge; a hoop surrounding said walls; a cover on the receptacle; and a fastener formed of two wires each extending over the top of the case, each 55 having hooked ends extending under the hoop and provided with means for tightening the wires.

2. In a shipping case, the combination of 60 a receptacle having annular walls flaring outwardly toward their upper edge; a hoop surrounding said walls; a cover on the receptacle; and a fastener formed of two wires each extending over the top of the case, each 65 having pointed hooks extending under the hoop and provided with means for tightening the wires.

In testimony whereof I have hereunto set my hand in the presence of two subscribing witnesses.

JAMES W. BROKAW.
